UNITED STATES PATENT OFFICE.

JAMES C. GEORGE AND GABRIEL L. GEORGE, OF BRISTOL, VIRGINIA.

FURNACE-GRADE.

1,220,216.

Specification of Letters Patent. Patented Mar. 27, 1917.

Application filed October 26, 1915. Serial No. 57,935.

To all whom it may concern:

Be it known that we, JAMES C. GEORGE and GABRIEL L. GEORGE, citizens of the United States, residing at Bristol, in the 5 county of Washington and State of Virginia, have invented certain new and useful Improvements in Furnace-Grates, of which the following is a specification.

This invention relates to a furnace grate 10 and more particularly to that class of grates most appropriately termed "sectional construction."

It is well known in the trade that furnace 15 grates burn out and are subject to renewal frequently and efforts have repeatedly been made to produce a properly designed sectional grate having the parts so disposed, arranged and constructed that when one part burned out, or was otherwise damaged, 20 a new part could be substituted therefor without difficulty. Furthermore, it is also a fact well known that, generally, the ends or hangers of the grate burn out first and therefore necessitate the renewal of the entire 25 grate.

Therefore, one object of the present invention resides in a construction of grate bar embodying a main bar carrying grate sections and hangers removable or detachable 30 from said main bar and grate sections but supporting the same in a furnace. Thus, should the hangers burn out it is possible to replace the same with new hangers at comparatively low cost when taking into 35 consideration the expense of an entire new grate or even the main bar.

A further object resides in the novel form of main bar and hangers which are so designed as to be comparatively simple and 40 cheap to manufacture.

And yet another object resides in the specific arrangement of main bar, hangers and grate sections.

With the above and other objects in view 45 one specific manner of practising this invention is shown in the accompanying drawing, in which:

Figure 1 is a view in perspective showing a grate bar constructed according to the 50 present invention, and with parts broken away to show the details of the hanger construction.

Fig. 2 is a central sectional view taken

longitudinally through a portion of the 55 grate bar.

Fig. 3 is a perspective view of one hanger; and

Fig. 4 is a perspective view of a modified 60 form of hanger for use with a rocking grate construction.

In detail:

The grate bar, as shown, comprises the main bar 1 which is substantially rectangular in form and is provided on the sides 2 with lugs 3 which serve to engage similar 65 lugs on the next adjacent grate bar and thus properly space the two apart. The ends 4 of the main frame 1 are provided with ears 5 for purposes to be hereinafter described. The sides 2 of the main bar 1, may at suitably spaced distances be reinforced by connecting webs 6.

The main bar 1 carries the grate sections 7 which are identical in construction and therefore interchangeable. Each of the sections 7 is substantially rectangular and includes a frame 8 provided on the sides with lugs 9 and on the ends with ears 10, the lugs 9 serve the same function as the lugs 3 on the main bar 1, while the ears 10 serve to 80 properly space the grate sections 7 apart. Each grate section 7 is provided, on the bottom, with the depending flanges 11 which are cut in at 12^a on each side to form shoulders for engagement with the sides 2 of the 85 main bar 1, whereas the flanges themselves depend within the main bar 1 and form a supporting medium for the sections 7 relative to the main bar which prevents displacement of the latter.

The hangers 12 (see Fig. 3) each comprise the top ledge 13 which may be suitably shaped on the outside to engage the furnace wall and on its inner edge is provided with lugs 14 to engage the ears 10 of 95 the next adjacent grate section 7. Depending from the ledge 13 is the hanger wall 15 which, at the bottom, extends inwardly, as shown at 16, and thence upwardly as at 17, thereby forming a hook-shaped seat to receive the ends 4 of the main bar 1.

In assembling the grate in a furnace, the hangers 12 are placed in position on the walls of the fire-box of the furnace and the main frame 1 then seated in the hangers as 105 shown in Figs. 1 and 2; the grate sections 7

resort to such modifications as fall within the scope of the invention as defined in the appended claims.

25

We claim:

1. A grate embodying a hanger having a lower hook-shaped seat, and a frame having one end abutting said hanger and engaging said seat.

30

2. A grate embodying a pair of hangers having lower hook-shaped seats, an elongated open frame having its ends abutting said hangers and engaged in said seats, and removable grate sections seated in said frame.

35

In testimony whereof we have hereunto set our hands in the presence of two subscribing witnesses.

JAMES C. GEORGE.
GABRIEL L. GEORGE.

Witnesses:

JAMES L. DAVIS,
J. J. ALLEY.

While, in the drawing and foregoing description, we have set forth a specific form of practising our invention, it is to be distinctly understood that, in practice, we may
